UNITED STATES PATENT OFFICE.

HAZEL E. TOWN, OF LIBBY, MONTANA.

SKIRT-MARKER.

1,153,733.

Specification of Letters Patent. Patented Sept. 14, 1915.

Application filed October 7, 1914. Serial No. 865,489.

To all whom it may concern:

Be it known that I, HAZEL E. TOWN, a citizen of the United States, residing at Libby, in the county of Flathead and State of Montana, have invented certain new and useful Improvements in Skirt-Markers; and I do hereby declare the following to be a full, clear, and exact description of the invention, such as will enable others skilled in the art to which it appertains to make and use the same.

My invention relates to improvements in skirt markers, and is intended to provide a yielding adjustable device for the purpose of marking the skirt at a uniform height above the floor, and without the necessity of calling in the assistance of anyone.

In order to provide the proper hang to the skirt, the general practice is for the dressmaker to try the skirt on the wearer, and make a mark all around the hem thereof at the desired height from the ground, so that the skirt may have a uniform length. Obviously, the wearer of the skirt cannot reach down and mark the hem thereof, and two persons are necessarily employed in the fitting process.

Various implements have been devised to accomplish the same result, and my invention is intended as an improvement upon such devices.

My invention will be understood by reference to the accompanying drawings, in which:

Figure 1 shows the device in use as applied to a door frame, vertical wall, or the like; Fig. 2 shows a section along the line 2—2 of Figs. 1 and 3, and looking down; Fig. 3 is a front elevation of the device, partly in section, along the line 3—3 of Fig. 2, and looking in the direction of the arrows; and Fig. 4 is a perspective view showing the head of the holder for containing the tailor's chalk, crayon, or other marking material.

A represents the vertical supporting member, such as a wall, door-frame, or the like, to which the device is applied.

B represents a bracket which is secured to the member A in any convenient way, as by screws C (see Fig. 2) passing through the holes b (see Fig. 3). This bracket B has guide grooves b' and overhanging flanges b'', to engage the ribs d of the slide D which is clamped to the bracket B at the desired height by means of the clamp screws E.

This slide D carries the frame F, provided with the socket piece F', which socket piece has a chamber preferably angular in cross-section to receive and hold against turning the heel g of the block G in which the crayon holder is held. This block G is provided with a chamber g' to receive the stem h of the holder H, which holder is provided with diverging jaws h', leaving a V-shaped slot h° in which the crayon K is held. This crayon has the engaging edge beveled, as at k. The heel g of the block G is normally pressed outward by the spring L, held in the chamber of the socket piece F', and it is normally held in engagement with said socket piece by a suitable holding device, such as the string M whose ends m are knotted in the socket d' in the slide D. (See Fig. 2). By this arrangement the marker may be pressed in against the action of the spring and yet is held against being pressed outward too far by the action of the spring.

In operation, the bracket B is secured to any vertical object, such as the wall, a door-frame, the side of a bookcase, or the like, and the marker is adjusted to the desired height by moving the slide D to the desired position and clamping the clamp screws E. The height of the marker would be obviously varied with the height of the person whose skirt is to be marked. The crayon K being set between the jaws h', and the heel h of the holder H being firmly set in the block G, the wearer whose skirt is to be measured moves into contact with the marker and, turning slowly around against the beveled edge k, a mark is made on the skirt. The spring L will cause the marker to yield to the configuration of the hips of the wearer of the skirt, so that a continuous mark will be secured. After the skirt is thus marked, it will be removed and the hem is turned up at the desired distance from the mark thus made.

It will thus be seen that I provide a yielding and vertically-adjustable device which is adapted to be adjusted to the height and configuration of the person or persons whose skirts are to be marked.

It will be obvious that various modifications might be made in the herein described apparatus, and in the construction, combination and arrangement of parts which could be used without departing from the spirit of my invention.

Having thus described my invention, what

I claim and desire to secure by Letters Patent of the United States is:—

1. A skirt marker of the character described, comprising a bracket, a slide adjustably mounted on said bracket, means for holding said slide in the desired position, a socket piece carried by said slide, a spring mounted in said socket piece, a block adapted to slide in said socket piece, and a marker holder having a V-shaped groove in the face thereof adapted to hold the marker crayon, said marker holder being attached to said block and adapted to reciprocate therewith under the action of said spring, substantially as described.
2. A skirt marker of the character described, comprising a bracket, a slide adjustably mounted on said bracket, means for holding said slide in the desired position, a socket piece carried by said slide, a coil

spring mounted in said socket piece, a block adapted to slide in said socket piece, a flexible connection attached to the heel of said block and passing through the center of said coil spring and being attached to the base 25 of said slide, thereby holding said block in said socket piece, and a marker holder having a V-shaped groove in the face thereof adapted to hold the marker crayon, said marker holder being attached to said block 30 and adapted to reciprocate therewith under the action of said coil spring, substantially as described.

In testimony whereof, I affix my signature, in presence of two witnesses.

HAZEL E. TOWN.

Witnesses:

JOHN H. TOWN,
JOHN M. GLEESON.
